UNITED STATES PATENT OFFICE.

ADOLF SONNENSCHEIN, OF NEW YORK, N. Y., ASSIGNOR TO HIMSELF AND
MAX SCHULHOF, OF SAME PLACE.

FAN ATTACHMENT FOR CHILDREN'S CARRIAGES.

SPECIFICATION forming part of Letters Patent No. 376,684, dated January 17, 1888.

Application filed April 7, 1887. Serial No. 234,007. (No model.)

To all whom it may concern:

Be it known that I, ADOLF SONNENSCHEIN, a subject of the Emperor of Austria-Hungary, residing at New York, in the county and State 5 of New York, have invented new and useful Improvements in Fan Attachments for Children's Carriages, of which the following is a specification.

My invention relates to an improved fan attachment for children's carriages and the like; and it has for its object to provide for a steady current of air while the carriage is in motion.

To such end my invention consists in the features of construction and combination of 15 devices, hereinafter described and claimed, reference being made to the accompanying drawings, in which—

Figure 1 represents a vertical section in the plane α α , Fig. 3. Fig. 2 is a side elevation 20 thereof. Fig. 3 is a plan or top view. Fig. 4 is a side elevation, on a smaller scale than the preceding figures, of a carriage provided with my fan attachment.

Similar letters indicate corresponding parts. 25 In the drawings, the letter A designates a fan-casing inclosing a rotary fan, B, Fig. 1, of any known construction. The horizontal fan-shaft C extends beyond the ends of the casing, and has bearings in boxes a a at each end of 30 the casing. Upon said shaft are aligned at a distance apart equal to the distance between the front wheels, E E, Fig. 4, of a carriage two friction-disks, D D, Figs. 1, 2, and 3, which are intended to come into contact with the peripheries of said wheels E E, whereby a rotary motion is imparted to said shaft and the fan is caused to revolve when the carriage is set in motion. The friction-disks are best made of soft rubber having a corrugated surface, which 35 disks can, if desired, be made adjustable on the shaft.

The casing A is suspended from the front of

the body F of the carriage by hinges b b , and it is free to move about the line of hinges, so that the weight of the attachment retains the 45 friction disks D D on the shaft C in contact with the wheels E of the carriage.

To lead the air from the mouth c of the casing above the body of the carriage, I make use of an education-tube, G, which is secured in 50 any convenient manner to the casing, and has a curvature or shape to suit the body of the carriage, in order that it may lie close to the same.

I am aware that a fan blower rigidly fixed 55 to a railway-car has been provided with a slot and a fan-shaft arranged in said slot and mounted in a gravitating frame, the shaft having at one end a friction-disk engaged by a friction-pulley on the car-axle. Such, therefore, I disclaim.

What I claim as new, and desire to secure by Letters Patent, is—

The combination, with a carriage-body and its supporting-wheels, of the fan-case A, 65 hinged to the body and provided with a stationary boxing, a , at each end, a tube, G, rising vertically from the fan-case and having its upper end bent laterally over the carriage-body to direct the air-currents upon the occupant, the fan-shaft C, extending through the case and boxings and projecting beyond each end of the case and swinging with the latter, and a friction disk, D, in each end of the fan-shaft respectively engaging the supporting-wheels of the carriage-body, substantially as 70 described.

In testimony whereof I have hereunto set my hand and seal in the presence of two subscribing witnesses.

ADOLF SONNENSCHEIN. [L. S.]
